UNITED STATES PATENT OFFICE

ARTHUR M. TROGNER, OF EAST ORANGE, NEW JERSEY, ASSIGNOR TO WIRED RADIO, INC., OF NEW YORK, N. Y., A CORPORATION OF DELAWARE

WATER COOLED TUBE ASSEMBLY

Application filed December 10, 1928. Serial No. 325,106.

This invention relates broadly to improvements in electrical apparatus and more specifically to improvements in sockets for electron tubes.

5 An object of this invention is to provide an electron tube socket from which the electron tube may be readily released for removal or replacement.

Another object of this invention is to provide 10 an electron tube socket in which efficient heat radiation is obtained.

A further object of this invention is to provide 15 a compact liquid cooled socket for liquid cooled electron tubes which efficiently removes the heat developed in the electron tube.

Other objects and features of this invention will be apparent to anyone skilled in the art from the following specification and 20 claims.

According to this invention the depending anode of an electron tube may be removably clamped in a compact and unitary cooling liquid structure. Inlet and outlet ports are 25 provided at the bottom of the structure thereby eliminating connections heretofore employed and which protrude from the sides, this providing a more compact unit. Clamping members are provided at the mouth of 30 the structure for engaging a rim surrounding the anode of the electron discharge device. These clamping members are readily slipped into engagement with the rim and provide means whereby the electron discharge device 35 is easily replaced. Adjusting screws are provided on the clamping members whereby the pressure exerted by said clamping members against the rim surrounding the anode may be varied. The inlet port is furthermore provided 40 with a curved passageway extending into the interior of the structure for imparting rotary motion to the water jet issuing from the inlet port. More effective cooling of the anode of the electron discharge device 45 is obtained in this manner.

In the drawings, Figure 1, partly in cross-section, illustrates one embodiment of this invention; Fig. 2 shows a cross-section along 50 the line 2—2 of Fig. 1; Fig. 3 shows a vertical

sectional view along the line 3—3 of Fig. 4 of the base of the electron tube socket; and Fig. 4 shows a cross-section of the socket structure along the line 4—4 of Fig. 1.

Like reference characters are used to designate like parts throughout all the figures of the drawings. Referring to Fig. 1 of the drawings in detail, 1 designates a liquid cooled electron discharge tube; 2 designates the depending anode of the electron discharge tube. A rim or flange 3 is provided on the anode for engagement with an inwardly extending flange 7' of the member 7. A tubular member 10 adapted to surround the anode electrode of the electron discharge device is fitted over the portion 11 of the plug member 13. A tubular member 9 adapted to enclose the tubular member 10 is fitted over the portion 12 of the member 13. The member 7 is adapted to engage the tubular member 9 at the end opposite to that engaging the member 13.

The electron discharge device 1 is placed with its anode 2 within the tubular member 10 and is supported upon the flange 7' by 75 the rim 3. Adjustable clamp members 4 in the form of rocker levers are supported by rod shaped pivot members 6 upon the member 7. Adjustable screw members 5 are screw threaded through the member 4. Portions of the clamp members 4 are adapted to engage the rim 3 to hold the electron discharge device in position with respect to the tubular members 9 and 10. Screw members 5 bear against portions of the member 7 and thereby provide means whereby the rigidity with which the electron discharge tube is held within the tubular members may be varied.

An electrostatic shield 8 is provided adjacent to the anode and flares out along the tube. 90 This shield is made, preferably, of relatively thin copper or brass spun into shape and secured by screws or other means to the member 7. The shield may be made integral with the member 7 if desired.

The plug member 13 is provided with the outlet and inlet ports 15 and 18, respectively. Pipe fittings 16 and 17 for making hose connections to the outlet and inlet ports 15 and 18 respectively are also provided in the plug 100

member 13. The inlet passage through the member 13 is helical in order to impart rotary motion to the cooling liquid entering the socket structure and facilitate cooling of the 5 anode 2. The pipe fittings 16 and 17 are provided at the bottom of the socket structure in order to reduce the cross-sectional area of the socket and render it less bulky. This type of construction lends itself more readily to design requirements and is also simpler in manufacture.

In Fig. 2 of the drawings is shown a cross-sectional view illustrating the manner in which the electron discharge device is secured in the socket structure. The clamping members 4 are slideable longitudinally of the pivot member 6 when the screws 5 are loosened. To remove the electron discharge tube it is only necessary to loosen the screws 5 and 20 slide the clamping members 4 on the pivot members 6 back adjacent to the support 19 out of engagement with the flange 3. The position of the clamping members 4 when the tube 1 is to be removed from the socket is shown in dotted outline in Fig. 2.

In Figs. 3 and 4 are illustrated the helical shaped passage of the liquid cooling medium inlet. The cooling medium passes up through the passage 18 into the space within the tubular member 10. The cooling medium then comes into contact with the anode of the electron discharge device and passes into the jacket formed between the tubular members 9 and 10 and out through the outlet port 15 as indicated by the arrows.

Although I have described this invention with respect to a particular construction it is, of course, understood that various modifications may be made in the detailed construction thereof without departing from the scope of this invention as defined by the appended claims.

What I claim as new and desire to secure by Letters Patent of the United States is as follows:

1. An apparatus of the class described, including an electron tube having an external anode and a source of electrons therefor, a pair of concentrically related jackets 50 arranged to receive said anode, means for circulating a cooling fluid around said anode and between said jackets, means adjacent the top of one of said jackets for securing said anode in position, said means comprising a pair of ball-crank levers, a supporting pivot therefor, screw tensioning devices extending through corresponding extremities respectively of each of said levers and means for sliding said levers along said pivoting means 55 in a plane perpendicular to that of the axis of said anode into diametrically opposite positions for engaging said anode and retaining by means of said tensioning devices said anode in said jackets.

65 2. An electron tube apparatus including a

thermionic tube having an external anode and a source of electrons therefor and comprising a socket structure arranged to receive said anode, a laterally extending flange on said anode, a head carried by said socket structure, a pair of rod members carried by said head, extending parallel to each other on opposite sides of and in a plane perpendicular to the axis of said socket structure, rockable levers mounted on said rod members and adjustable laterally on said rod members with respect to said head from diametrically opposite positions with respect to said flange on said anode to positions beyond said flange for securing or releasing said anode from 80 said socket.

3. A device of the class described including an electron tube having an external anode and a source of electrons cooperating therewith, a socket structure arranged to receive said anode, a laterally extending flange on said anode, a head carried by said socket structure, said socket structure comprising two fluid conducting members, a pair of parallel pivot rods carried by said head on opposite sides thereof, said rods being substantially perpendicular to the axis of said socket structure, rockable clamps carried respectively by said rods and slideable laterally along said rods and adjustable screws carried by each of said clamps and adapted when adjusted to bear against said head and lock said clamps into engagement with the flange of said anode to retain said anode in said socket structure.
